HOLDER FOR BOOKLETS

Meyer Mitnick, New York, N. Y.

Application May 24, 1943, Serial No. 488,132

1 Claim. (Cl. 281—17)

This invention relates to a holder for retaining a plurality of booklets, such as used for reference or any other utilitarian purposes, for example booklets containing coupons or stamps which may be therefrom extracted.

The principal object of the invention is to provide a holder for booklets, which will be conveniently and economically manufacturable, saleable at low cost, conveniently and efficiently utilizable, strong, durable, improved, which will at all times render the contents or pages of each booklet completely accessible for all purposes, and will fully expose the title cover of each booklet.

Other objects and advantages will hereinafter appear.

In the accompanying drawing:

Fig. 1 shows the sheet out of which the booklet holder of the invention is made.

Fig. 2 is a plan view showing the sheet as partially folded, during the manufacture of the holder.

Fig. 3 is an end elevation of the folded sheet shown in Fig. 2.

Fig. 4 is a cross-sectional side elevation, in an enlarged scale, showing the continued folding of the sheet, after it is formed as in Fig. 2, during the manufacture of the holder.

Fig. 5 is a perspective view of the booklet holder constituting the invention.

Fig. 6 is a perspective view showing the booklet holder as it appears when in opened condition and retaining the booklets.

The holder is made of a sheet 1, Fig. 1, of paper or other suitable material having requisite firmness, which sheet is elongated as shown and provided in its manufacture with longitudinal score lines 2, a series of transverse score lines 3, and a series of slits 4. Said sheet is first folded along the lines 2, with its side portions 5 disposed against the face 6 of its middle portion 7, thereby producing a collapsed tube-like form 8, as viewed in Figs. 2, 3. The form 8 is then folded along score lines 3 in the zigzag manner shown in Fig. 4, so that when thus collapsed there are furnished exterior leaves 9a with a plurality of interior leaves 9, as indicated in Figs. 5, 6, each

of which leaves exposes a flush wall 10 and surface corresponding to that in Fig. 3 opposing the face 6 and side portions 5 of sheet 1. Each of the interior set of leaves 9 consists of a pair of leaves 9b joined at folds 3a and depending from folds 3b, and each leaf 9b in turn consists of an exposed wall 10 backed by a pair of wall portions 5, while each exterior leaf 9a consists only of an exposed wall 10 backed by a pair of wall portions 5a. When the leaves, 9, 9a are thus collapsed and assembled to create the holder the exposed surface 10 of each thereof is provided with a transverse slit 4 near its end, as shown in Figs. 4, 6. The set of leaves are covered and bound together by pasting the side portions 5a of its exterior walls 9a to a heavy sheet 11 of paper or any other suitable material, in the manner shown in Figs. 5, 6, thereby providing tablet covers 11a with a backing 11b.

When it is desired to utilize the holder for the retention of a plurality of booklets, any booklet may be retained by any wall 10 of its leaves 9, 9a, by means of inserting its rear cover 12a through its slit 4 and lodging it between said wall and the wall portions 5 or 5a, in which manner the booklet is efficiently held in place upon the leaf with its title cover 12b in full view and all its pages and contents rendered completely accessible and available. It will be noted that the booklet may be as conveniently removed from the holder, by merely withdrawing its rear cover 12 from slit 4, and that its such insertion or removal from the holding leaf is performed with smoothness and without any liability to impediment whatever.

Having thus described my invention, I claim:

A holder for booklets comprising an elongated sheet having both of its side portions folded over one of the faces thereof, said folded sheet being additionally zig-zag folded transversely so as to form a set of leaves the exposed surfaces of which consist of the opposite face of said sheet, and the exposed walls of said leaves being slotted transversely near to their ends and parallel to said zig-zag folds for therethrough inserting covers of booklets for their retention.

MEYER MITNICK.
